UNITED STATES PATENT OFFICE.

RICHARD H. RICE, OF LYNN, MASSACHUSETTS, ASSIGNOR TO GENERAL ELECTRIC COMPANY, A CORPORATION OF NEW YORK.

TURBINE.

1,105,375.

Specification of Letters Patent. Patented July 28, 1914.

Application filed September 18, 1912. Serial No. 721,005.

To all whom it may concern:

Be it known that I, RICHARD H. RICE, a citizen of the United States, residing at Lynn, county of Essex, State of Massachusetts, have invented certain new and useful Improvements in Means for Enabling a Condensing-Turbine to Run Non-Condensing, of which the following is a specification.

This invention relates to elastic fluid turbines, and its object it to enable a condensing turbine to be easily altered into a non-condensing one without the necessity of elaborate accessories.

A condensing turbine is usually so designed that the drop from boiler pressure to atmospheric pressure is distributed among the several stages, each stage extracting its special portion of the energy of the steam. One or more stages are added in which the drop from atmospheric pressure to the vacuum pressure are utilized in wheels especially designed for that duty. Now when an attempt is made to run such a machine non-condensing, the wheels designed for the vacuum stages are as a rule worse than useless, throwing out the ratios of pressure drop for which the several wheels have been designed, and even putting a drag on the machine. It is, therefore, desirable to cut the vacuum wheels out of service under such conditions by exhausting the elastic fluid from an intermediate stage to atmosphere so as to shunt the final stages.

The object of the present invention is to provide an improvement arranged for this purpose.

In connection with condenser systems it is customary to provide an air relief valve which automatically opens when the vacuum is lost so as to connect the exhaust to atmosphere. In carrying out my invention I take advantage of this, and provide in the turbine, at the stage where the steam drops down to atmospheric pressure, a valve opening directly into the exhaust pipe. The steam will, therefore, leave the turbine and escape through the relief valve of the condenser, thus cutting out of service the stage or stages which are designed to run between atmospheric and vacuum pressure. Moreover, the wheel or wheels in said cut out will not be shut up in a closed chamber, but will run idly in chambers open to the atmosphere through the condenser and will thus be saved from injurious heating.

For a consideration of what I believe to be novel and my invention, attention is directed to the accompanying description and the claims appended thereto.

In the accompanying drawing, Figure 1 is a side elevation of a horizontal steam turbine equipped with my invention; Fig. 2 is a longitudinal section of a portion thereon, and Fig. 3 is an end view, partly in section.

The drawing shows three stages 1, 2 and 3, the first two being respectively high and low pressure stages, while the latter is designed to run on the vacuum and exhaust into the conduit 4 which is connected to a suitable condenser as for example a condenser of the jet or barometric type. In the low pressure stage 2, the steam is assumed to fall to about atmospheric pressure. A chamber 5 communicates with this stage, and, with the port 6 opening into the conduit 4, forms a passage for connecting stage 2 directly with said conduit. This chamber 5 is formed by extending the diaphragms on opposite sides of the stage 2, the extension on the right forming a portion of one of the walls of the exhaust conduit. A valve 7 of the rotary type is seated in the passage and controls the port 6. This valve can be opened and closed by any suitable means, such as the hand wheel 8, the worm 9, and the segment worm gear 10 on the spindle of the valve 7. An indicator 11 shows the extent to which the valve has been opened. The volume of the elastic fluid in the stage 2 is quite great and it is, therefore, necessary that the port 6 be of substantial size in order to properly handle it. The port, therefore, is made to extend substantially across the turbine, as best shown in Fig. 3. By this arrangement of the valve and passage I provide a structure which economizes space and enables the parts to be assembled without an increase in the dimensions of the wheel casing.

Whenever it becomes necessary to change over the operation of the turbine from condensing to non-condensing, the only thing to be done is simply to open the valve 7. This cuts out the vacuum stage 3 and allows the steam which has dropped to atmospheric pressure in stage 2 to exhaust directly to the atmosphere through the relief valve of the barometric condenser. Since stage 3 is open to the atmosphere, the wheel in that

stage can run with no danger of overheating.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

1. The combination in an elastic fluid turbine of the condensing type, of means for connecting an intermediate stage of the condenser when the turbine is run non-condensing, said means comprising a narrow passage of substantially the width of the turbine, and a valve of the rotary type controlling the same.

2. The combination in an elastic fluid turbine of the condensing type, of means for connecting an intermediate stage to the condenser when the turbine is run non-condens-

ing, said means comprising a passage formed 25 by extending the diaphragms on opposite sides of said intermediate stage, and a rotary valve controlling the same.

3. In an elastic fluid turbine, the combination of a casing, diaphragms dividing the 30 casing into a plurality of stages, rotors in each stage, and exhaust conduit for the final stage, the walls of the diaphragm of an intermediate stage being extended to form a narrow passage extending substantially 35 across the turbine, one of said extensions also forming a wall of the exhaust conduit and having a horizontally extending port therethrough of substantially the length of the wall, a rotary valve controlling said 40 port, and means for operating said valve.

In witness whereof, I have hereunto set my hand this fourteenth day of September, 1912.

RICHARD H. RICE.

FRANK H. JOHNSON.

Copies of this patent may be obtained for five cents each, by addressing the "Commissioner of Patents,
Washington, D. C."

It is hereby certified that in Letters Patent No. 1,105,375, granted July 28, 1914, upon the application of Richard H. Rice, of Lynn, Massachusetts, for an improvement in "Turbines," errors appear in the printed specification requiring correction as follows: Page 1, line 52, before the word "will" insert the word *stages*; page 2, line 15, for the word "of" read *to*; same page, line 32, for the word "and" read *an*; and that the said Letters Patent should be read with these corrections therein that the same may conform to the record of the case in the Patent Office.

Signed and sealed this 10th day of November, A. D., 1914.

[SEAL.]

R. F. WHITEHEAD,

Acting Commissioner of Patents.
